UNITED STATES PATENT OFFICE.

SYLVANUS D. LOCKE, OF HOOSICK FALLS, NEW YORK.

HARVESTER-BINDER.

SPECIFICATION forming part of Letters Patent No. 251,906, dated January 3, 1882.

Application filed June 12, 1879.

To all whom it may concern:

Be it known that I, SYLVANUS D. LOCKE, of Hoosick Falls, in the county of Rensselaer and State of New York, have invented a certain new and useful Improvement in Harvester-Binders; and I do hereby declare the following to be a full, clear, and exact description of the same, reference being had to the accompanying drawings, forming part of this specification, in which—

Figure 1 is a top plan view of a harvester having my improvements applied thereto. Fig. 2 is an end elevation of the same. Fig. 3 is a rear elevation of a portion of the same. Fig. 4 is a detail view, showing the position of the binding-arm while ejecting a bound gavel. Figs. 5 and 6 are detached views of the castings and traveler-rods upon which the frame of the binding mechanism is supported and adjusted. Fig. 7 is a top plan view of the plate *o* detached. Figs. 8, 9, 10, and 11 are views showing the details of the twisting and cutting mechanism.

Similar letters of reference in the several figures denote the same parts.

The object of this invention is to improve the construction and operation of automatic grain-binding machinery; and to this end the invention consists, first, in an improved construction for the adjustment of the binding-head and band-carrying arm to the length of the grain or the position of the grain on the binding-table; secondly, in an improved means for accomplishing the movement of the band-carrying arm; thirdly, in an improved separator and compressor; fourthly, in an improved spring device to assist the looping-hooks by guiding and bending the wire properly during their operation; and, lastly, in the several combinations of mechanism whereby the general objects of the machine are carried into practice.

In the drawings, *A* represents the harvester, which, in the form here shown, contains the usual cutter, *a*, the platform *a'*, an endless apron-carrier, *a²*, an elevator, *a³*, draft-tongue *a⁴*, draft-wheels *a⁵ a⁶*, driver's seat *a⁷*, and binding table or platform *B*, these several parts, with their necessary and usual accessories, being of any approved form and construction.

Upon an offset, *a⁸*, of the harvester-frame there are attached, by screws or otherwise, two

castings, *F*, having terminal upright lugs *f* and lateral flanges *f'*. A single casting with terminal and middle lugs will answer the same purpose. Two traveler-rods, *f²*, are supported by the lugs so as to extend parallel to the upper surface of the castings between the lugs, as shown. The rods may be secured by pins, keys, or other means, so as to be removable when desired. These two rods pass through downwardly-extending projections or legs *g* of an upright movable frame, *G*, which supports and adjusts the binding head and arm. Near their ends the castings are provided with flanges *f³ f³*, behind which the legs of the frame *G* will be securely held while the traveler-rods are introduced and secured in place. By means of a lever, *H*, the driver from his seat can slide the frame *G* back and forth upon the traveler-rods, and thus adjust the position of the binding mechanism to the length or position of the grain on the binding-table. The upper end of the frame *G* is stayed and guided by braces *J J'*, secured to a sliding guided plate, *J²*, which devices are made the subject of a pending application for Letters Patent filed by me, and therefore need not be specifically described herein.

C is the main driving-wheel which actuates the holding and twisting mechanism and the band-carrying arm. It is continuously rotated in the direction of the arrow by any suitable means—as, for example, by circumferential cogs meshing into a sliding feathered pinion *85* or trundle, *k*, on a shaft, *K*, which in turn is driven by any suitable connection to the main power shaft or wheel of the harvester. The sliding pinion *k* automatically adjusts itself on its shaft to the position of the main wheel *C*, as the latter may be from time to time adjusted by the movement of the lever *H*. The shaft *D* of wheel *C* passes horizontally through the lower arm of the casting *G*, and, projecting at the angle or corner thereof, is provided with a bevel-pinion, *d*. The latter meshes into a similar pinion, *d'*, on the lower end of a vertical shaft, *D'*, which has its bearings in the upright part of the casting *G*. At the upper end of the vertical shaft *D'* is another bevel-gear wheel, *d²*, having only a mutilated-gear rim and provided with suitable delay-surfaces, which wheel *d²* drives intermittently a bevel-gear, *d³*, on the end of a horizontal shaft, *D²*,

having its bearings in the upper arm of the casting. At the opposite end the shaft D^2 is provided with a crank, d^4 , which actuates the band-carrying arm I . The latter is curved, as shown, and is at its upper end articulated to a bar, I' , which in turn is articulated to the top of an arm, g' , projecting upward from the top of the frame or casting G . By means of the crank and the articulated arm, combined as aforesaid, a peculiar movement is imparted to the band-carrying arm, which movement is fully represented in Fig. 3. When the band-carrying arm arrives at the point represented at 2 in said figure the wheels d^2 d^3 run out of gear and the arm remains in that position till the cutting and twisting is effected, when said wheels again come into gear and the arm moves forward to the point marked 3, thereby ejecting the bound gavel from the machine. The arm then rises and moves back rapidly, its point following the course of the dotted line in the direction of the indicated arrow. At the lower end of the casting G is an arm, g^2 , projecting up by the side of the wheel C , which arm supports a bracket, C' , having a flat top which extends over said wheel, and at the opposite side of the wheel is provided with a downwardly-elongated tubular bearing, g^3 , containing a hollow vertical shaft, m , within which is arranged a longer vertical shaft, n . Shaft m carries at its lower end a small pinion, m' , and delay-plate m^2 , and at its upper end a revolving hooked arm, e , while shaft n carries at its lower end a similar pinion, n' , and a delay-plate, n^2 , and at its upper end an S-shaped looping and twisting hook, s . On the side of wheel C there is arranged a segment-gear rim, c , which actuates the pinion n' , and some of whose teeth c' are elongated, so as to mesh with the wheel m' and give it one revolution. Grooves c^2 c^3 permit the rotation of the delay-plates when the gear-rims are in engagement, as aforesaid, while the smooth face of the wheel C at other times, being in contact with said plates, holds the shafts m n from revolving.

Immediately above the revolving hooked arm e is a flat sharp-edged or square-edged steel plate, r , and above this plate is a spring steel plate, o , which presses upward with yielding force against the under side of the hook s . The shaft n passes through one end of the plates r o , while screws u serve to secure their opposite ends upon a rib or projecting surface, g^4 , of the arm g^2 . The upper edge of the hook e revolves in close contact with the under side of the plate r , for the purpose of acting in connection therewith to sever the wire; but beneath this hook e is a holder-plate, on which the end of the wire is clamped by said hook, as hereinabove described. The ends of the wire are snubbed over the plate o by the initial movement of the twister, and in its further revolution are clamped and held in their snubbed condition between its arms and the plate. The latter therefore must have considerable area, that the ends of the wire may

be properly supported. One mode of constructing it is shown in Fig. 7. As there represented it is recessed in its upper surface immediately around the shaft n , so as to form an annular depression or bed, v , around said shaft. It is also cut away at v' , and from the angle of the gain or notch thus cut out a groove, v^2 , leads into the depression or bed v . This plate 75 o fills up the space under the twisting-hook s , and it acts with a yielding force to admit the wire to enter between it and the hook. The primary function of this plate, as above stated, is to hold the wire close up under the twisting-hook, thereby bending it at an abrupt angle and causing it to be held without danger of slipping or drawing out of the hooks as the twister revolves. The function of the recess v and its surrounding rim or flange is to guide 80 the wire close to the shaft while twisting, thus preventing its ends from escaping from the twisting-hook until properly twisted. The groove v^2 is to facilitate the passage of the wire into the recess v , and the lateral notch v' is to 85 guide the wire into the groove v^2 . The operation of these binding devices will be more 90 fully explained hereinafter.

T is a separating and compressing arm, projecting downward from an arm, g^5 , of the casting G . It is secured to said arm by a lateral arm or trunnion journaled therein, which permits the lower end of the separator or compressor to be rocked or swung backward and forward. A stop, t , limits its backward swing 100 and a spring, t' , holds it normally back against the stop with a yielding force.

The binding-table is provided with the usual guides, B' B' , slot B^2 , and yoke B^3 , and it is secured to the casting G , so as to be adjusted 105 therewith and always preserve the same relation to the binding mechanism. The means for thus securing it are immaterial; but bolts or screws passing into or through the head of the arm g^2 and another similar arm will answer the 110 purpose as well.

To the upper surface of the binding-table, at the side of the slot, there are secured a flanged and notched metal plate, b b' , and a flanged underlapping plate, b^3 , which two plates form 115 a peculiar gateway for the passage of the band-carrier, as well as a guide and holder for the band material. They also serve to deflect the grain and dirt away from the slot and protect the working parts underneath; but these 120 flanged and notched plates and the gateway formed by them form subject-matter in Letters Patent No. 238,939, granted to me March 15, 1881, and are not claimed herein.

The mode of operation of the above-described 125 machine is as follows: The wire is first put through the eye of the needle or arm, and the end is temporarily held in the usual manner, as by the hand of the operator or by being fastened at any point on the arm near its articulation with the crank. The machine is then started up, causing the arm to sweep downward and forward and bring the wire into the hook-notch b^2 . The arm then stops by the un-

meshing of gears d^2 d^3 , while the wheel C continues to revolve. As it revolves several of the gear-teeth c engage with the pinion n' and turn the twisting-hook about three-quarters of a revolution, causing one of its arms to catch hold of the wire and bend it over the top of plate o. Then the long gear-teeth c' come in contact with the pinion m' and revolve the arm e once around, whereby toward the end of its revolution it seizes and clamps the wire between it and the top of the part g³ beneath, and cuts off the upper end of the wire by forcing it against the sharp-edged plate r; the hook s meanwhile continuing to revolve. Then the pinion m' passes off of the long teeth, while the pinion n' , still engaged with the short teeth, continues to revolve, carrying the hook s around several times, and at length becomes disengaged after a full number of revolutions, leaving the hooks in their original position, with the end of the wire clamped and the machine ready for work. It will be observed that to accomplish these movements there are several short teeth of rim c arranged in advance of the long-tooth rim c', whose first function is to reverse the hook s before the clamping-hook e begins to operate. There may be four, six, or any other suitable number of these advanced teeth that will properly accomplish this object, and will rotate the twister far enough in advance of the cutter to loop the ends of the band underneath the former and prevent their being withdrawn by the expansion of the bundle, or otherwise, before the twisting is completed, as described. The number of long teeth should be equal to the number of teeth on pinion m' , so as to cause one revolution thereof. The whole number of teeth which act on the pinion n' should be some integral multiple of the teeth n' , in order to give it a desired number of full revolutions, which number may be greater or less, as it may be preferred to twist the band more or less. The machine, having been thus prepared, is put to its work, and the cut grain from the elevator is dropped upon the binding-table behind the separator T, which, in connection with the wire held in the needle or band-carrying arm, keeps the grain from passing too far forward. The arm I rises, passes back above the grain, and descends, carrying the wire around the gavel, and then sweeps outward, compacting and condensing the gavel against the compressing-arm T, which yields, swings forward, and rests on the front and upper side of the gavel as the arm I reaches the point where it stops with the wire in the notch b². Immediately before the arm I reaches that point the hook s begins to rotate, and, engaging one of its curved arms with the clamped strand, carries it around to the opposite side of the shaft n, while the other curved arm is presented in position to receive the advancing strand carried by the needle or arm I. As this strand is in turn seized by the hook s the band-carrying arm ceases for a time to move and awaits the completion of the twisting. Almost simultaneously the clamp arm e passes out from

under the plate r and releases the end of the clamped strand, and then for an interval the hook twists the two strands while neither of them is clamped; but when the arm e comes around it engages with the strand held by the band-carrying arm, clamps it as before underneath, and cuts it off above. Both strands are now cut off and free from the clamp, but still engaged with the hook, whereby they have been drawn into the recess v and clamped with a yielding force between the spring-plate o and the under side of the hook s. The latter continues to rotate and completes the twist, which secures the band to the gavel. The band-carrying arm then begins to move forward again behind the bound gavel, forcing the ends of the band from the hook and ejecting the gavel from the machine. As the gavel passes out from under the spring-compressor the latter springs back quickly to a vertical position, forcing the unbound grain back on the binding-table and effectually separating the straws of the old gavel from those assembling to form a new one. In this operation it is assisted by the wire extending from the holding-clamp to the rising needle, which raises the loose straws above the line described by the point of the separator and supports them for the moment upon an incline, down which they are easily swept by the backward-springing rod. The grain thus assembling piles up against the rear side of the vertical separator. The band-carrying arm continues to rise, passes quickly back over it, descends, separates the grain to form another gavel, condenses it forward against the separator, which now acts again as a compressor, and the operation of the parts is repeated as before.

The wire is supplied from a spool or reel of any suitable construction in any approved manner. The wire-reel and tension apparatus herein shown, as well as the grain-reel, form the subjects of other contemporaneous applications for Letters Patent filed by me, and need not be herein described. I do not limit myself to the precise form or construction of the parts herein shown and described, but consider any mere modifications thereof which do not alter the principle and mode of operation of the machine or its respective parts or combinations as coming within the scope of my invention.

By the term "continuously-rotating wheel" C, I do not mean necessarily a wheel rotating at all times continuously, but rather a wheel rotating continuously while the band-holder and twisting-head are in action, it being immaterial whether the movement of the wheel C be continuous or intermittent at other periods; but it is a material element to this part of the mechanism that the wheel rotate continuously from the time of commencing to loop or twist the wire till the twisting is completed and the gavel moved out of the way.

I claim as my invention—

1. In combination with the adjustable supporting-frame of the binding mechanism, the casting or castings F, having ears or lugs which

- serve as stops to limit the movement of said frame, and the removable traveler-rods f^2 , passing through and having their bearings in said lugs.
- 5 2. The casting F, formed with lugs for the reception or support of the traveler-rod, and a guard or flange for the initial reception and retention of the legs of the binding-frame.
3. The combination of the frame G, the continuously-rotating wheel C beneath the frame, the band - securing mechanism immediately driven by said wheel, the binding-arm, and the shafts and gears forming a direct train between said binding-arm and wheel, whereby the parts are driven by the latter and timed in unison.
4. In combination with a gaveling-arm, the oppositely-acting vertical spring compressor and separator supported from an overhanging portion of the frame.
- 20 5. In combination with a rotary twister, the elastically - yielding snubbing and clamping plate o, underlying the arm or arms of said twister, substantially as described.
6. In combination with a rotary twister, the elastically - yielding snubbing and clamping plate, formed with annular depression v, gain or notch v' , and guide-grooves v^2 .
7. The combination of the twisting-hook, the spring snubbing and clamping plate o, the plate r, and the cutter e, substantially as described.
8. The continuously-rotating driving-wheel, an intermittently-operating band-carrying arm driven by said wheel through a direct train-connection therewith, and intermittently-operating band-securing devices immediately driven by said wheel, combined substantially as described.
9. The combination of the continuously-rotating driving - wheel, the supporting - frame, having top and bottom horizontal arms joined by a vertical side arm or post, the three shafts contained in said arms, and connected at the angles by beveled-gear wheels with a stop-motion in the train, and the needle or binding arm driven intermittently thereby, substantially as described.

SYLVANUS D. LOCKE.
